CLOTH FINISHING

Sanford L. Cluett, Troy, N. Y., assignor to Cluett, Peabody & Co., Inc., Troy, N. Y., a corporation of New York

Application June 7, 1933, Serial No. 674,636

9 Claims. (Cl. 38—8)

This invention relates to cloth finishing and has for its principal object the improvement of method and mechanism employed in enhancing the surface luster of fabric, in drying fabric, and in softening and improving the "hand" of sized fabric. It is a further object of the invention to avoid, when desired, stretching of the fabric during such treatment. My invention also aims to accomplish these objects without detriment to the body feel of the fabric, in particular without causing the fabric to acquire a feel suggestive of that of paper, such as results from treatment by a calender wherein fabric is reduced in thickness; furthermore, my invention is intended for the treatment of cloth to break down a "papery" feel, to break down starch adhesions, to soften the cloth and to render it heavier in feel or texture.

The invention also aims to carry out the above treatment in a minimum of space, and to act on the fabric in such a way and by such mechanism that the fabric will be treated equally on both surfaces. An object of the invention is accordingly to subject the fabric to heating and polishing and to flexure in one direction tending to soften the fabric, and then to subject the cloth to heating and polishing action applied to its opposite surface and to flexure in a reverse direction from the initial flexure, and to do this repeatedly within a small space and by simple mechanism.

Although the above objects may be accomplished according to my invention without shrinking the cloth, in a preferred instance of my invention the cloth is first shrunk by instrumentalities cooperating with the drying, softening and finishing mechanism of the machine. Mechanism constructed according to the present invention is particularly adapted to operate in conjunction with cloth shrinking mechanism to dry, soften and finish the cloth after the shrinking operation without causing stretching tending to decrease the net attained shrinkage, and is furthermore adapted thus to act on the cloth with equal effect on both surfaces thereof.

Other objects of invention, and features of advantage and utility will be apparent from this specification wherein one instance of the invention is explained by way of example.

The present application is in part a continuation of my application Serial No. 550,189, filed July 11, 1931, for Letters Patent on Heated roll or drum, and in the preferred machine illustrated herewith employs the construction

originally described and claimed in that application.

In the drawings:

Fig. 1 is a side elevation of mechanism exemplifying this invention;

Fig. 2 is a vertical half-section on the line 2—2 of Fig. 1;

Fig. 3 is a fragmentary end view of the machine, partly broken away;

Fig. 4 is a diagrammatic side elevation showing particularly the directions of travel of the cloth and its treating mechanism, certain of the driving connections of the mechanism being omitted for clarity;

Fig. 5 is a vertical section on line 5—5 of Fig. 1, 15 radially through one of the hollow heating drums of the machine;

Fig. 6 is a fragmentary view similar to Fig. 5 and to a larger scale, showing one end only of the drum; and

Fig. 7 is a fragmentary vertical section on line 7—7 of Fig. 3, illustrating the manner of application of pressure blocks to the cloth approaching the nip point of the first roll and drum.

Referring to Figs. 1, 2 and 4, the illustrated machine is particularly adapted to receive at the right of the machine a cloth web W, to be dried, softened, polished and finished, and to carry this web W through a sinuous path (Fig. 4) defined by lower and upper series of rotatable heated drums 11, 11^a and 11^b, and 12, 12^a and 12^b.

At approximately the level of, and interspersed between, the lower series of hot drums 11, 11^a and 11^b, there is preferably provided a series of pressure rolls 13, each disposed in close proximity to one of the hot drums; a similar series of pressure rolls 14 is preferably provided in association with the upper series of hot drums 12, 12^a and 12^b.

Operating in conjunction with the lower series of hot drums 11 and pressure rolls 13 there is provided an endless blanket or web-carrier belt 15, passing as shown in Fig. 4 from suitable idler rolls 17 and 19 to the right-hand pressure roll 13 of the lower series, thence in a sinuous path 45 around each of the hot drums 11, 11^a and 11^b and pressure rolls 13 of the series, over an idler roll 21 and back to idler roll 17.

Another similar endless blanket or web-carrier belt 16 travels from idler rolls 20 and 18, over 50 an idler roll 24, to the right-hand pressure roll 14 of the upper series, thence in a sinuous path around each of the hot drums 12, 12^a and 12^b and pressure rolls 14 of that series, around an idler roll 22 and back to idler roll 20. One im-

portant function of the two endless web-carriers 15 and 16 is to confine the cloth web W, under treatment, to pressure contact with each of the hot drums 11, 11^a and 11^b and 12, 12^a and 12^b.

By way of example of frame structure suitable for mounting these instrumentalities, the machine is illustrated as having frame end uprights 30 joined by longitudinal upper and lower members 31, 32 (Fig. 1), and by transverse upper and lower members 33, 33^a, 34, 34^a (Figs. 2 and 3). Upper and lower beams 36 and 37 extending longitudinally of the machine between end uprights 30 on both sides of the machine may serve to support the respective upper and lower series of hot drums and pressure rolls. Preferably the hot drums are mounted in fixed positions on the beams 36, 36, and 37, 37, and each pressure roll movably mounted and yieldingly urged toward the next adjacent hot drum. Referring to Figs. 1, 2 and 3, journal bearings 13^a on opposite ends of the pressure rolls 13 may be held in swinging frames 13^b which are connected to the beams 37 by pivotal connections 13^c. Any suitable springs, indicated at 13^d (Figs. 1 and 2), may be employed to urge the swinging frames 13^b and their pressure rolls 13 toward the adjacent hot rolls. The upper pressure rolls 14 may be similarly mounted.

The idler rolls 17 and 18 of the lower web-carrier may conveniently be mounted in brackets 41 at opposite sides of the machine, with the idler roll 17 carried by blocks 43 movable up and down by screws 45 which are operated through worm and gear connections by a hand wheel 47 to loosen or tighten the web-carrier 18. The idler rolls 18 and 20 of the upper web-carrier may be similarly mounted in brackets 42, with idler roll 18 similarly adjustable by hand wheel 48.

Each of the hot drums 11, 11^a and 11^b, and 12, 12^a and 12^b of the machine, preferably constructed as described in my copending application Serial No. 550,189, filed July 11, 1931, comprises as shown in Figs. 5 and 6, a hollow outer cylinder 50 provided with opposite heads 51 and 52 mounted to turn on ball bearings 53 and 54 at opposite ends. The inner races of the ball bearings are mounted on relatively stationary thick tubular members 55 and 56, extending from the opposite beams 36 or 37 of the machine frame. Within the outer cylinder 50 thus rotatably mounted is provided a stationary cylinder 60 in close proximity to, but not touching, the outer cylinder, and of sufficient strength to hold heated fluid such as steam under any desired pressure. The space separating these two cylinders is preferably only that required for a running clearance between them; a clearance of about one-sixteenth of an inch or less is desirable. The opposite ends of this inner stationary cylinder are suitably closed, as by heads 62 and 63, into which the tubular members 55 and 56 are fastened.

The tubular members 56 of the several hot drums 11 and 12, adapted to supply steam thereto, are connected at one side of the machine (Fig. 1) to a suitable header or supply conduit 65 leading to a supply of steam. Valves 66 enable the supply to the individual hot drums to be controlled. At the opposite end of each drum there is preferably fitted into the tubular member 55 a pipe 69 which is bent down at its inner end to receive the condensation of steam from the inner cylinder 60. The tubular members 55 of the several drums 11 and 12 are preferably connected by any suitable connections 70 (Fig. 3) to a trap or the like, adapted to receive the condensate of the steam.

The driving connections for the hot drums and pressure rolls are shown as including a horizontal shaft 80, a vertical shaft 81, and a horizontal shaft 82, mounted in bearings on the machine frame and geared together. Upper and lower horizontal drive shafts 80 and 82 carry bevel gears 84 adapted to rotate corresponding bevel gears 85 which are fast on cross shafts 86 carrying suitable pulleys 87. Suitable belts 88, running on these pulleys 87 and on pulleys 90 on hot drums 11^a, 11^b and 12^a, 12^b serve to rotate these drums at the desired speeds. The hot drums 11 and 12 may likewise be belt driven in the same manner if desired.

The shafts 80 and 82 also preferably carry bevel gears 84 adapted to rotate corresponding bevel gears 96 which are fast on cross shafts 95 carrying suitable pulleys 97; one of these pulleys 97 is indicated in Fig. 2. Suitable belts 98 running on these pulleys 97 and on pulleys 100 on the pressure rolls 13 and 14 drive these pressure rolls. The driving connections are illustrated as proportioned to rotate the hot drums 11^a and 11^b and 12^a and 12^b at a considerably higher surface speed than the surface speed of pressure rolls 13 and 14, for example, ten times higher. The web-carrier belts 15 and 16 which are preferably of felt have sufficient frictional contact with the series of driven rolls 13 and 14 to prevent slippage relative thereto, and hence travel at the same speed as these rolls. Hot drums 11 and 12, herein shown as rotated by the action of the web carrier belts 15 and 16 travel at the same speed. The hot drums 12^a, 12^b, and 11^a and 11^b, driven by belts 89, rotate at higher speeds as just explained, and exert a polishing action on the web of cloth under treatment; all of the hot drums preferably have very smooth polished surfaces so as to be capable of slipping readily with respect to the web W. The relatively high temperature of these hot drums further aids in facilitating slippage in polishing. If desired, for certain conditions of operation, each of the hot drums 11, 11^a and 11^b, 12, 12^a and 12^b may be belt driven by belts 89; also under certain conditions when polishing action is not desired, only the series of pressure rolls 13 and 14 need be driven by belts 98, all of the hot drums then traveling at the speed of the web carrier belt.

As mentioned above, the invention aims to subject the cloth to repeated flexure in alternate directions without causing the thus treated cloth to be longer than before treatment. I have discovered that this effect can be obtained by a disposition of the coacting rolls and drums such that in running onto each hot drum the cloth and the web-carrier belt are nipped between the hot drum and the associated pressure roll, whereas in leaving the hot drum the cloth is not subjected to such nipping action. Thus in the illustrated machine, each pressure roll 13 and 14 is urged toward its adjacent hot drum by the described springs 13^d, so as to nip the cloth web at the point where it attains contact with the hot drum. As clearly shown in Fig. 4, there is a substantial gap to the left of each hot drum between the hot drum and the next succeeding pressure roll, so that no nipping action occurs at the point where the cloth web leaves the hot drum.

The functioning of so much of the apparatus as has been thus far described will now be apparent. Cloth coming into the right-hand end of the machine in a somewhat moist condition (for example, containing 10% of moisture) will be dried by contact with the successive hot drums of

the machine. The drying action of these drums, applied first to one side, then to the other of the cloth, will substantially completely dry the cloth during the complete passage of the cloth through the machine. It will be understood that in general each individual hot drum will only partially dry the cloth, the cloth not attaining its desired state of dryness until at or near the end of its travel through the machine. By subjecting the cloth to repeated bending or flexure in alternate directions concomitantly with the drying, the crystal formation of the sizing of the cloth and the adhesions of starch within the cloth are broken down, rendering the cloth softer than usual, although preserving and in fact enhancing the body feel of the cloth, rendering the cloth apparently heavier than before treatment. The ironing and polishing action of the hot drums, being alternately and repeatedly applied to the two faces of the cloth, gives the two faces the same surface characteristics. The luster of the cloth is improved by the polishing action of the hot drums, also without detriment to the "feel" or softness of the cloth.

25 The machine's ability to subject cloth to the described finishing treatment without delivering the cloth in a stretched condition is an improvement over the usual ironing machines which deliver the cloth fixed in a state of stretch or elongation and hence increasingly subject to shrinkage in laundering.

It is contemplated that the cloth treated by my improved machine may be cloth having its original trade finish substantially unimpaired and preshrunk or rendered non-shrinkable in length, as by the process of my United States Patent No. 1,734,896, dated November 5, 1929, or by the process of my application Serial No. 445,300, filed April 18, 1930, Patent No. 1,861,422, dated May 31, 1932. In such use, the invention provides for improving the finish of the cloth in the respects herein described, equally on both sides of the cloth, without impairing the non-shrinking quality of the cloth.

45 The mechanism of the present invention is especially adapted to include instrumentalities for effecting a lengthwise shrinkage of the cloth preferably according to the inventions described and claimed in my Patents Nos. 1,861,422, 1,861,423 and 1,861,424, dated May 31, 1932.

Referring to Fig. 7, the web carrier belt 15 is preferably of substantial thickness, for example, one-quarter of an inch. In passing over the right-hand pressure roll 13 the outermost surface of the belt on this roll is expanded in length, whereas in passing about the hot drum 11, the same surface of the belt is materially contracted. In passing from roll 13 to drum 11 at the nip point between the members the belt reverses in flexure, 55 its originally outer elongated convex surface in contact with the cloth web becoming a shortened concave surface. By confining the cloth web W by pressure against the belt before and during such contraction of the belt, the cloth may be caused to partake of the contraction, thus becoming shorter in length. Means for compressing the cloth in this manner is herein shown as including a series of pressure blocks 130 (Figs. 7, 3 and 4) conforming to the curvature of the belt on roll 13 and extending substantially to the nip point between roll 13 and drum 11. The cloth web W is firmly held in contact with the convex surface of belt 15 by these pressure blocks; then at the nip point is transferred from pressure confinement 60 between the blocks 130 and belt 15 to similar confinement between belt 15 and hot drum 11, with no substantial interval of release from such confinement. By this means the cloth thus caused to partake of the contraction of the belt is compressively shortened in length an amount which may, for example, be 2 or 3 inches per yard, the amount of such lengthwise shortening depending on the diameters of roll 13 and drum 11 and upon the thickness of belt 15.

5 The swinging frames 13b associated with the lower right-hand pressure roll 13 may be suitably extended to the right, as shown at 13b1 in Fig. 7, to have fastened thereto a transverse channel bar 133 adapted for positioning and steadyng the pressure blocks 130. Each pressure block 130 is preferably provided with a lip or projecting plate 135 extending to the right (Fig. 7) under the channel bar 133 and adapted to bear upwardly against the head of a bolt 137 which thus prevents the block 130 from being caught at the nip point between roll 13 and drum 11. A spring 138 may be employed to steady the pressure block 130 by urging this block to swing about bolt 137 as a fulcrum, against the web W. Preferably the several pressure blocks 130 are heated, to prevent sticking; this is conveniently accomplished by the inclusion within them of electric heating elements 140, connected by wires 141 to any suitable source of current. Referring now to Fig. 4, there may be located at an appropriate distance from the entrance end of the series of rolls, for example 25 5 to 20 feet therefrom, a pair of feed rolls 108, 109 adapted to nip the web of cloth W, and positively driven through a variable speed gear VS from a main drive shaft 110. The main drive 30 shaft 110 preferably is connected to the shaft 80 of the set of rolls through the intermediary of another variable speed gear VS' as diagrammatically shown. Any suitable moistening device 120 may be located between the feed rolls 108, 109 35 and the first pressure roll 13, for the purpose of imparting to the web W a sufficient moisture content (usually about 10% by weight) if the web is not already moist. The effect of such moistening on most fabrics not already shrunk in filling 40 is to cause widthwise shrinkage; such shrinking action may be increased by stretching the web W between rolls 108, 109 and 13 by suitably adjusting one or the other of the variable speed gears VS or VS'. A suitable series of scrimp bars 45 115 may be employed to prevent longitudinal wrinkles from passing, and to present the web W to the first pressure roll 13 in a widthwise straightened condition.

55 By proper adjustment of the variable speed gear VS or the similar gear VS', the cloth, finished by improvement of its body and surface characteristics, may be delivered at a definite and predetermined rate, which may (within limits) bear any desired ratio to the speed of entry of 60 the untreated cloth between input rolls 108 and 109. By adjusting the delivery rate of the web-carrier belts 15 and 16 to equal the surface speed of rolls 108 and 109, the longitudinal stretch involved in the initial widthwise shrinkage will be 65 exactly offset by the longitudinal shrinkage imparted at the entry of the cloth between the first pressure roll 13 and the hot drum 11. By causing the delivery rate of the web-carrier belts 15 and 16 to be less than the speed of rolls 108 and 70 109, the cloth may be delivered in a lengthwise shrunken or contracted state.

The amount of shrinkage induced at the first pressure roll 13 and hot drum 11 will be substantially constant for any given dimension of these 75

parts, shape of blocks 130 and kind and thickness of belt 15; this amount of shrinkage may be, for example, 2 inches per yard. In that case by causing the belt 16 to deliver the cloth at 34/36 5 the rate of input between rolls 108 and 109, the maximum longitudinal shrinkage capacity of the given machine may be realized in an equal net shrinkage of the completely treated finished web. Any net shrinkage less than the maximum capacity 10 it may be attained by increasing the rate of delivery with respect to the rate of input, thus subjecting the cloth to some longitudinal stretch before longitudinally shrinking it. My above co-pending application Serial No. 516,972 is in part 15 directed to such procedure.

The present invention provides for the complete control over the treated web throughout a drying, starch-breaking, polishing and finishing process following the longitudinal shrinking operation without loss even in part of the shrinkage attained by such shrinking operation, and without impairing the range of adjustment of the net final shrinkage attained.

I claim:

25 1. Cloth finishing mechanism having therein opposed series of smooth rotatable drums adapted to polish cloth, and a pair of endless web-carrier belts, one passing in a sinuous path about one series only of the drums and the other passing 30 in a sinuous path about the other series only of the drums, the drums and belts being so disposed with respect to each other that a web of cloth can pass around drums of the two series in alternation in contact therewith, under the confinement 35 of the corresponding carrier belts.

2. Cloth finishing mechanism having therein in combination, means for subjecting a traveling cloth web to repeated relatively abrupt flexures in alternate directions a plurality of times in 40 each direction by defining a path of travel in the form of successive reverse curves, and means for exerting confining pressure normal to the cloth as it passes around said curves, and means for polishing the thus confined cloth alternately on 45 both surfaces.

3. Cloth finishing mechanism having therein in combination, means for polishing a traveling web of cloth repeatedly on alternate surfaces thereof, a plurality of times on each surface, and 50 means for subjecting the cloth intermediate the several successive polishing operations to abrupt changes of flexure such as will soften sizing in the cloth, said polishing means including means for drying the cloth.

55 4. Art of finishing cloth which comprises conveying the cloth lengthwise and during such travel subjecting the cloth to repeated polishing action on alternate surfaces thereof, a plurality of times on each surface, while applying heat to 60 dry the cloth, and intermediate the several successive polishing operations subjecting the cloth to abrupt changes of flexure such as will soften sizing, starch or the like in the cloth.

5. Art of finishing cloth which comprises conveying the cloth lengthwise, and during such travel subjecting the cloth to successive polishing operations applied to alternate surfaces there-

of, a plurality of times on each surface; applying heat to dry the cloth, and, without substantially stretching the cloth, subjecting it to abrupt changes in flexure between the several successive polishing operations.

6. Cloth finishing mechanism having therein a pair of traveling web-carrier belts, means including opposed series of heated drying drums for defining sinuous paths of travel for said belts, the said belts and drums being arranged 10 to permit a web of cloth to be conveyed alternately around drums of the opposed series in contact with each drum and its associated belt, means for causing the cloth web to be supplied by one of said belts to one of the drums in a 15 longitudinally contracted state, and means for maintaining the speeds of the two belts equal, so as to deliver the cloth from the last drum without loss of its condition of longitudinal contraction.

20 7. A cloth finishing mechanism adapted to operate on a traveling cloth web, having therein in combination, opposed series of rolls defining a path of travel for said web imparting repeated 25 abrupt flexures to the web in alternate directions, traveling blankets adapted to press the web against and in contact with said rolls as the web travels around said rolls, and guide means for the blankets positioned to nip the blankets against the web and roll at each point where the 30 web runs onto one of said rolls and to release the web from the pressure of the blanket without nipping at each point of departure of the web from said roll.

35 8. A cloth finishing mechanism adapted to operate on a traveling cloth web, having therein in combination, opposed series of rolls defining a path of travel for said web imparting repeated 40 abrupt flexures to the web in alternate directions, traveling blankets adapted to press the web against and in contact with said rolls as the web travels around said rolls, and guide means for the blankets positioned to nip the blanket against the web and roll at each point where the web 45 runs onto one of said rolls and to release the web from the pressure of the blanket without nipping at each point of departure of the web from said roll, the machine including means for causing the blankets and the rolls to travel at different surface speeds, thereby repeatedly to 50 polish the web alternately on both surfaces.

9. A cloth finishing mechanism adapted to operate on a traveling cloth web, having therein in combination, opposed series of heated rolls defining a path of travel for said web imparting 55 repeated abrupt flexures to the web in alternate directions, traveling blankets adapted to press the web against and in contact with said rolls as the web travels around said rolls, and guide means for the blankets positioned to nip the blanket against the web and roll at each point where the web runs onto one of said rolls and to release the web from the pressure of the blanket without nipping at each point of departure of the web from said roll.

SANFORD L. CLUETT.
